UNITED STATES PATENT OFFICE.

GUSTAV MARBURG, OF VIENNA, AUSTRIA-HUNGARY.

SUBMERGED WATER-WHEEL.

SPECIFICATION forming part of Letters Patent No. 707,857, dated August 26, 1902.

Application filed April 21, 1900. Serial No. 13,802. (No model.)

To all whom it may concern:

Be it known that I, GUSTAV MARBURG, a subject of the Emperor of Austria-Hungary, residing at Vienna, Austria-Hungary, have 5 invented new and useful Improvements in Submerged Water-Wheels, of which the following is a full, clear, and exact description.

The present invention relates to submerged water-wheels; and it consists of the details 10 of construction hereinafter set forth, and particularly pointed out in the claims.

In many cases where submerged water-wheels are employed they cannot be mounted at a sufficient depth below the water-surface 15 to allow of the passage of deep-draft vessels, and in such cases they form an impediment.

According to the present invention the water-wheel is divided in the middle and the two halves are capable of being sprung apart, 20 so that they will lie in a direction parallel with the banks of the river or stream.

In order to render the present specification easily intelligible, reference is had to the accompanying drawings, in which similar letters of reference denote similar parts throughout the several views.

Figure 1 is an elevation, partly in section, 30 of a water-wheel constructed according to the present invention. Fig. 2 is a sectional plan on the line A B of Fig. 1, showing the coupling of the two wheel parts at the center or thereabout of the stream; and Fig. 3 is a side elevation of one-half of a modified form of water-wheel.

The water-wheel consists of the two vertically-divided parts *a* and *b*, having stub-shafts 35 *k* at one end of each half, by means of which the said half is mounted to rotate in vertically-adjustable bearings *m* and *n* of any suitable 40 or well-known construction. These bearings are mounted, respectively, on the vertically-disposed standards *e* and *h*, arranged one at each side of the stream or river, and the said bearings *m* and *n* may be vertically adjusted 45 on the said standards in any suitable manner. For instance, the bearings may be suspended on lines or chains (indicated by dotted lines *e'*) and capable of being raised or lowered by means of the winches *e''*, mounted 50 at the top of the standards. The standard *e* has a lower roll *f*, adapted to move on the foot-plate *g* in the arc of a circle the center

of which is the vertically-disposed power-transmitting shaft *c*, and the stub-shaft *k* of the wheel-half *a* carries behind the standard 55 *e* a bevel-gear engaging a similar gear on the power-transmitting shaft *c*, which is coupled at its upper end to the power-shaft *d* by means of bevel or chain or other suitable gearing. The bevel-gears of the water-wheel shaft *k* 60 and the vertical shaft *c* are retained in engagement when the water-wheel is swung around by means of a yoke *m'*. The standard *h* simply turns on its lower pivot, which is mounted in the foot-plate *i* and free to 65 turn therein. The water-wheel halves are covered by a half-mantle *p p*, the two halves of which may be connected together by a latch-lever *s*, Fig. 2, which serves to make one rigid structure of the two half-mantles, 70 but permits of their separate removal. These mantles inclose the upper part of the water-wheels, so that the motion of the current will only act on the lower parts of the same in 75 one direction to cause them to turn; otherwise they would stand still or simply swing on their stub-shafts, as will be readily understood. The latch *s* must be of sufficient strength to resist the force of the current. The ends of the water-wheel halves are 80 coupled by a set of flanges *q* and *r*, Figs. 1 and 2, which engage one within the other, the coupling-latch *s* of the mantles *p* preventing the disengagement or swinging apart of 85 the coupling-flanges *q* and *r* when in the horizontal position during rotation. The interior ends of the wheel may be supported by floats or buoys *o o*, several of which may be employed, if necessary. Instead of the floats or buoys the mantle *p* might be made with 90 double walls, so that the air between the same would serve as a float to buoy up the wheel-halves.

The device operates in the following manner: If a deep-draft vessel is passing, the wheel 95 is stopped by any suitable means, so that the coupling-flanges *q* and *r* will be arrested in the horizontal position. The two halves of the mantles are then unlocked by throwing back the latch-lever *s*, and then the wheel-halves will be free to float apart. The flanges being in the horizontal position will simply float out of engagement. The wheel-halves will thus turn around on their guide-stand-

ards *e* and *h* and lie along the banks of the river or stream, so that the vessel or other body may pass between them. When this has taken place, the wheel-halves are swung back, either by means of chains or any other suitable means, the flanges will pass into engagement again, and the mantle-halves *p* must then be recoupled by means of the latch-lever *s*. The wheel-halves may also be pulled apart by means of chains or other suitable means.

The modification of the device shown in Fig. 3 enables the wheel to be employed for streams or rivers of different widths, the blades of each half of the wheel being adapted to telescope one into the other, the said blades being normally retained in position by means of fixed intermediate disks. Any suitable joints may be employed for the ends of the wings, such as shown at *u'* in Fig. 3. For instance, the ends of one set of blades may pass into sockets at the ends of the other set and the wheels may be telescoped together when it is required to employ the same with narrow waters. These wheels may be mounted and controlled in a similar manner to those described with reference to Fig. 1. As shown in the drawings, the blades are spirally turned in order to render them more efficacious.

30 I claim as my invention—

1. The combination of a submerged water-wheel vertically divided in the middle and means for allowing the two parts of the same to swing apart substantially as described.

35 2. The combination of a water-wheel divided into two parts vertically, a horizontally-

disposed stub-shaft to support each part of the same at the outer end, means for coupling the two parts together and means for allowing the supporting-shafts to swing apart in the horizontal plane and separate the two wheel parts substantially as described.

3. The combination of a water-wheel divided into two parts, means for supporting each part of the same at the outer end and floats to sustain the inner ends of the same, a coupling to connect the two parts at their adjacent ends and means for allowing the two parts to swing apart horizontally in the manner and for the purpose substantially as described.

4. The combination of a water-wheel consisting of two parts, means for coupling the two parts at their adjacent ends, stub-shafts at the outer ends one to carry each wheel-half, vertically-adjustable bearings for the said stub-shafts in the manner and for the purpose substantially as described.

5. The combination of a water-wheel consisting of two parts, means for supporting each part rotatably at its outer end, a coupling to couple the said parts at their adjacent ends and means for adjusting the length of each part to suit currents of different breadths substantially as described.

65 In witness whereof I have hereunto set my hand in presence of two witnesses.

GUSTAV MARBURG.
